UNITED STATES PATENT OFFICE.

HERBERT H. HOLBROOK, OF ARCADIA, OKLAHOMA.

HAT-BOX.

1,157,538.

Specification of Letters Patent. Patented Oct. 19, 1915.

Application filed January 25, 1915. Serial No. 4,307.

To all whom it may concern:

Be it known that I, HERBERT H. HOLBROOK, a citizen of the United States, residing at Arcadia, in the county of Oklahoma and State of Oklahoma, have invented certain new and useful Improvements in Hat-Boxes; and I do hereby declare the following to be a full, clear, and exact description of the invention, such as will enable others skilled in the art to which it appertains to make and use the same.

This invention relates to hat boxes, designed more particularly for use in holding ladies' hats, in millinery stores, or in clothes closets in the households, and one of the principal objects of the invention is to provide a hat box having a hinged top cover and a hinged side cover so that the box when placed on a shelf with other articles or boxes on top of the same may be readily opened at the front or side of the box without disturbing the other boxes.

Another object of the invention is to provide a box having a top cover by means of which a hat may be placed in the box from the top without disturbing the side or end cover, and when it is required to remove the hat from the box, the end or side cover may be opened without disturbing the articles or boxes on top of the box containing the hat.

The foregoing and other objects may be attained by means of the construction illustrated in the accompanying drawing, in which—

Figure 1 is perspective view of a hat made in accordance with this invention and shown closed, Fig. 2 is a perspective view of the hat box with both top and side covers opened, and Fig. 3 is a sectional view taken on the line 3—3 of Fig. 1.

Referring to the drawing, the numeral 1 designates the bottom of the box, 2 is one side, 3 is the other side and 4 is the back of the box. The top cover 5 of the box is connected by means of fabric hinges 6 to the sides 3, and stop tapes 7 are secured to the cover 5 and to the back 4 of the box to limit the outward throw of the cover. At the front of the box a cross-piece 8 is provided, said cross-piece being connected to the sides 2 and 3, and a limiting tape 9 is connected to the cross piece 8 at one end and at the other

end is connected to the cover 5. The front cover 10 of the box is provided with angularly bent side members 11 and connected to these members are tapes 12 which extend up and out through openings 13 in the side members 2 and 3, and when the cover 10 is up in closed position, the tapes 12 are tied in a bow knot as shown at 14.

The top cover 5 is provided with a slot 15 in the downwardly extending flange 16 and a similar slot 17 in the top portion, and a tape 18 extends through said slot and around the box and is connected by means of a knot 60 or bow 19 at one side of the box.

From the foregoing it will be obvious that the hat box can be manufactured at comparatively low cost, is reliable and efficient for its purpose, can be opened on top for 70 placing the hat therein and opened on the side or front when it is desired to remove the hat from a shelf containing a number of other boxes.

In order to cover the hat in the box two 75 pieces of paper *a* may be connected one to the back portion 4 and the other to the cross piece 8 so that the article in the box may be covered and protected.

Various changes may be made in the details of construction without departing from the spirit and scope of the invention as defined in the claims.

What is claimed is—

In a hat box having a bottom, side walls 85 and a rear wall, a cover hinged to one end of the side walls, a front wall hinged to the bottom, angular bent side members formed integral with the front wall, a cross piece secured to the front upper edge of side walls, 90 flexible members secured to the brace and to the rear wall; tape members secured to the angular bent side member of the front wall, said tape members extending through slots in the side walls, the free ends of said tape 95 members being adapted when tied together to secure the front wall in a closed position.

In testimony whereof I affix my signature in presence of two witnesses.

HERBERT H. HOLBROOK.
